UNITED STATES PATENT OFFICE

RUDOLPH FRANK STEHLIK, OF CHICAGO, ILLINOIS, ASSIGNOR TO RESERVE HOLDING COMPANY, OF CHICAGO, ILLINOIS, A CORPORATION OF DELAWARE

MULTIOFFICE TELEPHONE SYSTEM

Application filed March 14, 1927, Serial No. 175,187. Renewed January 25, 1930.

This invention relates in general to multi-office telephone systems but more particularly to such systems as comprise in one network offices or exchanges of two different kinds, the offices of one kind being manual offices wherein connections are completed by operators, while the other kind of offices are automatic offices whose connections are completed by means of automatic switches, and the object of the invention is to provide new and improved circuit arrangements for handling interoffice calls between the automatic and manual exchanges.

Systems having both kinds of exchanges as above pointed out are becoming quite common and may arise either by consolidation of existing manual and automatic systems, serving the same territory, or by the process of changing over a manual system to an automatic system. Usually in the latter case only one office at a time is converted from manual to automatic and it follows that during the period of transition there will necessarily be both kinds of offices in operation. However the above situation may arrive, it is necessary to provide suitable circuit arrangements for handling calls from the manual to the automatic offices, and from the automatic offices to the manual offices. The present invention is concerned only with the latter class of calls, and provides certain improvements in systems comprising automatic to manual trunks which are accessible to selector switches in the automatic offices and terminate in plugs in front of a B operator at the manual office, together with call registers for registering the digits in telephone numbers called by automatic subscribers when the trunks are taken for use, and an indicating device upon which such numbers are shown to the operator one after the other as fast as she can complete the desired connections.

The present invention may be considered to be an improvement on the system disclosed in Patent No. 1,539,925, issued June 2, 1925. The main feature of the invention may be said to consist in the provision of improved plug ended cord circuits for completing calls from automatic exchanges to subscribers whose lines terminate in a manual call indi-

cator office. One of the features of the improved cord circuit consists in the provisions for giving the automatic subscriber a busy tone from the cord circuit.

Another feature consists in the provision for busying at the automatic exchange, the two conductor outgoing trunks extending to the manual call indicator exchange under various operating conditions which are encountered.

A still further feature consists in the provision of an improved pre-selecting rotary line switch for preselecting idle register sets, together with the special method of multiplying the various register sets at an intermediate distributing frame.

A still further feature of the invention consists in the provision for completing a call which may come into an operator's position after the last of the normally used register sets is taken into use and before all the trunks leading to the operator's position have been made busy.

Other features consist in the provision for positively guarding an idle register set against seizure in case it does not properly release; in the provision of an improved time switch which releases each time a digit is dialled; in the provision of circuit arrangements whereby the same circuit which cuts off the ringing current also transmits ringing induction; and in the provision of various other detailed improvements, all of which will be pointed out and described fully in the detailed description which follows:

In the drawings, comprising Figs. 1, 2, 3, and 4, there is shown by means of the usual circuit diagrams the apparatus and circuit connections thereof which is involved in a complete connection extending from the automatic substation A, Fig. 1, to a manual substation A', Fig. 2.

The apparatus indicated in Fig. 1, is located in an automatic exchange, while the apparatus indicated in Figs. 2, 3, and 4, is located in a manual exchange. Inasmuch as the automatic switching equipment itself and the manual equipment are both well known and of the usual type, no detailed description of the mechanical features of this apparatus will

be given, except in so far as it is found convenient or necessary to do so in the explanation of the operations of the circuits.

Referring to Fig. 1, the substation A is one of a plurality of ordinary automatic substations terminating in the automatic exchange previously referred to, and is provided with the usual talking equipment and ringer, and also with a calling device of a well known type which is indicated by the reference character S, through the medium of which the subscriber controls the central office switches.

The line conductors 11 and 12 extend to the exchange where they terminate in the line switch C, which may be briefly described as a rotary line switch whose moveable terminals or wipers have no normal position, and which have movements in a forward direction only.

The construction of a line switch of this type is well known in the art, and its function, also well understood, is to extend its associated line when calling to an idle trunk line. In carrying out this object, a plurality of these individual line switches are given access to a group of trunk lines extending to first selector switches. One of the trunk lines to which the line switch C has access is shown in the drawing as extending to the first selector D, which is a vertical and rotary selector of the well known Strowger type. In a multi-office system of the kind herein contemplated the first selector switches are usually known as office selectors and the selector D in common with a plurality of similar selectors has access to a plurality of groups of trunk lines, each of which group may extend to a different office or exchange in the system. Some of these groups of trunk lines may extend to automatic exchanges, while other groups may extend to manual exchanges.

A trunk line in one of the latter groups is shown in the drawing, and comprises the repeater E and the trunk line conductors 130 and 131, which extend to the manual exchange in question and there terminate in a plug ending cord circuit O, Fig. 2. The cord circuit O is one of a plurality of similar cord circuits at a B operator's position in the manual exchange and constitutes the means whereby the trunk line shown may be connected by the operator with anyone of the manual lines terminating in the manual exchange. One of these lines is the line of substation A', which with its associated line equipment is shown at the right of Fig. 2.

The repeater E is an automatic impulse repeater of the general type in common use, and in addition to repeating operating impulses to the distant manual exchange, provides holding circuits for the automatic switches, and thus renders it unnecessary to use more than two conductors for the inter-office trunk line.

From the foregoing, it will be understood that the operation of an office selector, such

as the selector D, in response to the calling of the first digit in the telephone number of a line in the manual exchange, will result in extending the connection from the line of the calling automatic subscriber to an idle plug ending cord circuit in the manual exchange. In order to take care of the remaining digits in the number, there is provided for each B operator's position a plurality of register sets as hereinbefore stated, each set being suitable for registering all the digits in a telephone number, with the exception, of course, of the first digit which controls the office selector in the automatic exchange. In Figs. 3 and 4, I have shown one of these register sets complete. It comprises register control switch RCS, Fig. 3, the register switches R¹, R², R³ and R⁴, Fig. 4. The register control switch RCS, which may be described briefly, consists essentially of wipers 355 and 356 and their associated sets of bank contacts, together with a stepping magnet 359 for advancing the switch wipers, and a release magnet 358 for restoring it to normal. A set of rotary off-normal springs 357 are included in the circuit of the latter magnet and are closed on a first movement of the switch. Since the switches are all alike mechanically, it will be unnecessary to describe the others.

The indicating device by means of which called telephone numbers are shown to the operator is shown in Fig. 4, where it is indicated by reference character V, and comprises essentially a plurality of groups of switchboard lamps, there being one group of lamps for each register switch in a register set. It will be understood that the lamps have the function of illuminating the digits of the called numbers and causing them to stand out so as to be readily distinguished. The digits are preferably marked in black on the reverse side of a white semi-transparent surface and ordinarily are not very conspicuous. But when the switchboard lamp immediately behind a character or figure is lighted such character or figure will stand out very clearly and is read with great facility. The lamps of the indicating device are wired to the bank contacts which are associated with the wipers 404, 424, 444 and 464 of the several register switches of the register set shown, and are also wired to similar contacts in the banks of the register switches of the other register sets at the position.

As stated hereinbefore, there are a plurality of register sets providing for the registration of a plurality of calls simultaneously or close together. These registered calls are displayed on the indicating device one after the other as fast as the operator can complete the connections by plugging into the multiple jacks which correspond to the numbers displayed. In order to switch the calls over onto the indicating device in succession

a so-called consecution control switch is provided. This switch is shown in Fig. 2 where it is indicated by the reference character CCS, and comprises a single wiper, and a bank of contacts as shown in the drawing. The switch CCS is mechanically the same in construction as the rotary line switch C, Fig. 1, that is, its wipers have no normal position and move in a forward direction only. The circuits, however, are changed and will be described hereinafter.

Each register set is provided with a time controlled switch which in the case of the register set shown in Figs. 3 and 4, is indicated by the reference character P, Fig. 3. The switch P may be similar in construction to the register control switch but is operated by timing mechanism. The time mechanism, which may be common to the exchange, is indicated by the reference character T, and may consist of any suitable kind of interrupter controlled mechanism which is adapted to provide impulses at the rate of about one per second.

In order to promptly extend calls which are received at the manual exchange to the register sets, each cord circuit is provided with an individual rotary line switch which is maintained positioned before an idle register set when not in use. These line switches have common access to all the register sets. The reference character C', Fig. 3, indicates a rotary type line switch which is individual to the cord circuit O Fig. 2, and which has access to the register set shown in the drawings and also to the other register sets which are provided at the B operator's position in which the cord circuit O terminates. The line switch C' is of well known construction and function and on this account will not be described in detail as to its mechanical operation. The banks of the line switch C' are what is known as 25 point banks. The banks of the register selectors at the position are connected in multiple and a cable connects the multiply connected banks with one side of the intermediate distributing frame, indicated I. D. F., Fig. 4, from which point they are jumpered to the various register sets in different multiple combinations as will be more fully explained hereinafter.

Referring again to Fig. 2, there is shown in the lower right hand corner, a trunk circuit TC which extends to an information and complaint operator's position. When an incomplete telephone number is displayed, the B operator will plug into the trunk circuit TC thereby connecting the calling party to the information and complaint operator. The latter operator either completes the call or advises the calling party of his error.

Relay ATB, in Fig. 2, is what is known as the all trunk busy relay. This relay is common to the register sets at this particular B operator's position, and when operated artificially renders all the trunks extending

from the automatic exchange to the B operator's position busy.

At TK in Fig. 2, there is shown one of a plurality of similar keys by means of which the B operator may busy the trunks coming into her position in groups of eight.

In the dotted rectangle marked POS. 3, Fig. 2, there is shown an operator's position linking key for the B operator at position 3; at POS. 2 there is shown the position linking key for the B operator at position 2, which position is the position where cord circuit O is located, and at POS. 1 there is shown in the dotted rectangle the position linking key for the B operator at position 1. The position linking keys are for the purpose of permitting an operator at an intermediate position to link or connect her head set to the cord circuits of positions on either side of her position.

In the upper left hand corner of Fig. 2, there is illustrated at MB the bus-bar to which the main battery is directly connected. The conductor 273 illustrates the fuse wire by means of which the main battery is connected to the lower bus-bar and the conductor 274 illustrates the means by which all the apparatus at the operator's position is connected to main battery, it being understood that all the battery symbols shown separately in the drawing are in reality connected to conductor 274.

In the upper part of Fig. 3, there is shown the set-up-pilot lamps SUP by means of which the B operator is enabled to know which register sets are in use.

In the lower part of Fig. 3, there is shown by means of the usual circuit diagrams the method of connecting up the first seven register sets so that they may be normally available for use, while the eighth or reserve register set is normally made busy. When all the first seven register sets are busy, the eighth register set is then rendered available for use to take care of any call which may have come in after the seventh or last register set was seized and before all of the trunks were made busy.

Having described in a general way the layout of the system herein disclosed, the operation of the system will now be described more in detail, it being assumed for this purpose that the subscriber at substation A, Fig. 1 desires to obtain a connection with the manual subscriber at substation A' Fig. 2, whose telephone numbers, it will be assumed, it 23456. When the receiver is removed at substation A, a circuit is completed over the line conductors 11 and 12 for the line relay 14 of the individual line switch C. Upon energizing, line relay 14 completes at its armature 20 a circuit which extends to the switching relay 13 and stepping magnet 15 in series to battery, and at its armature 19 connects the test wiper 26 to the above cir-

cuit at a point midway between the switching relay and the stepping magnet. The operation now depends upon whether the first selector trunk upon which the wipers of the line switch are in connection is busy or is not busy. 5 If the trunk line is busy, the test contact 31 associated therewith will have a ground potential upon it, the switching relay 13 will be short circuited, and the stepping magnet 15, which interrupts its own circuit, will operate as a buzzer to advance the wipers 25-27, inclusive, step-by-step in search of an idle trunk line. This operation will continue as long as the test wiper 26 continues to engage 10 grounded or busy test contacts. However, we may assume that in the present case when a call is initiated the selector D is idle, and the test contact 31 therefore is not grounded. Under these circumstances when the line relay 14 is energized the switching relay 13 is 15 energized immediately afterwards, with the result that the line conductors 11 and 12 are disconnected from the winding of the line relay 14 and from ground, respectively, and are extended by way of armatures 16 and 18 and their working contacts, wipers 25 and 27, bank contacts 30 and 32, and armatures 60 and 62 and their resting contacts, to the 20 upper and lower winding of the line relay 50 of the selector D.

As soon as the line is extended to the selector D as above described, the line relay 50 will be energized and will close the circuit of the slow acting release relay 51. Upon 25 energizing, the latter relay prepares the circuit of the selector for operation in its vertical movement in the usual manner, and also completes a holding circuit extending back to the line switch C as follows: ground, working contact of armature 63 and said armature, conductor 64, bank contact 31, test wiper 26, armature 17 and its working contact, winding of the switching relay 13, and the winding of the stepping magnet 15 to battery. It is understood that the above holding 30 circuit is completed before the slow acting relay 14 has had time to deenergize. In addition to maintaining the switching relay energized, the holding circuit also serves to provide ground to the multiples of test contact 31 and also to the multiple test contacts in which the private normal conductor 28 terminates in the banks of the connectors which have access to the line of sub-station A, thereby 35 guarding the connection against intrusion in the customary manner.

The calling subscriber may now operate his calling device S in accordance with the first digit of the desired number. Two interruptions are thereby produced in the circuit of the line relay 50, and the said relay is accordingly twice deenergized momentarily, transmitting at each deenergization an impulse of current through the slow-acting series relay 52 and the vertical magnet 56

to battery. By the operation of a vertical magnet the selector shaft is raised two steps, whereupon the wipers 70 to 72, inclusive, will be standing opposite the level of bank contacts in which are terminated the trunk lines 70 extending to the manual exchange. The slow-acting relay 52 which is energized in series with the vertical magnet, retains its armature attracted throughout the vertical movement of the switch, and upon the closure 75 of the vertical off-normal springs 59 completes a circuit for the stepping relay 53. Upon energizing (relay 53 prepares a circuit for the rotary magnet 54 at its lower armature and at its upper armature establishes a locking circuit for itself. At the end of the vertical movement of the switch, the slow-acting relay 52 is deenergized and closes the 80 circuit of the rotary magnet, which is thereupon energized to advance the wipers 70 to 85 72 inclusive, into engagement with the first set of bank contacts in the level opposite which they were raised. The rotary magnet 54 also breaks the locking circuit for the stepping relay 53 which accordingly deenergizes and breaks the circuit of the rotary magnet, which thereupon deenergizes also, and again closes its interrupter contact.

The operation now depends upon whether the trunk line with which the wipers are connected is busy or is not busy. If the trunk line is busy the test contact associated therewith will be grounded and the stepping relay 53 will be energized over a circuit which extends by way of the test wiper 71, armature 100 61 and its resting contact, off normal springs 59, interrupter contact of the rotary magnet, and the winding of stepping relay 53 to battery. The stepping relay will therefore again close the circuit of the rotary magnet 105 54 which will operate to rotate the switch wipers into engagement with the next set of bank contacts. This operation in which the stepping relay and the rotary magnet are alternately energized and deenergized will continue as long as the test wiper 71 continues 110 to engage grounded or busy test contacts. In the present case, it will be assumed that the trunk shown in the drawing is the first idle trunk line, and when therefore the test 115 wiper arrives at test contact 74 and the rotary magnet is deenergized, the stepping relay 53 will not again be operated, but instead the switching relay 55, which heretofore has been short circuited, will be energized by current flowing over the following path: ground, conductors 64, winding of the switching relay 55, off normal springs 59, interrupter contacts of the rotary magnet 54, and the winding of the stepping relay 53 to battery. Owing to the high resistance of the switching 120 relay 55, stepping relay 53 is not operated. Upon energizing, relay 55 disconnects the incoming line conductors from the winding of the line relay 50 and extends them by way of 125 130

armatures 60 and 62 and their working contacts, wipers 70 and 72, bank contacts 73 and 75, trunk conductors 76 and 78, and normally closed contacts of the reversing relay 100, to the upper and lower windings of the line relay 101 of the repeater E.

When the line is extended to the repeater as above explained, the line relay 101 is energized and closes a circuit for the slow acting release relay 102. Upon energizing, relay 102 completes a holding circuit extending back to the selector D and the line switch C as follows: ground, armature 112 and its working contact, conductor 77, test contact 74, test wiper 71, and the armature 61 and its working contact to conductor 64, where it joins the previously described holding circuit extending back to line switch G. The above described circuit serves to maintain relays 55 and 13 energized throughout the duration of the connection.

In addition to closing the holding circuit for the automatic switches C and D, the relay 102 of the repeater E prepares a circuit at its armature 115 for the slow acting relay 103; closes a circuit at its armature 114 for energizing relay 104; and at its armature 113 completes a circuit for energizing the line relay 206 of the cord circuit O, Fig. 2 over the following path: from ground by way of the normally closed springs controlled by armature 118, working contact of armature 113 and said armature, conductor 130, armature 214 and its resting contact, upper left hand winding of the repeating coil of the cord circuit O, normally closed springs controlled by armature 237, and upper winding of the line relay 206 to battery. Upon energizing, line relay 206 causes the energization of the release relay 205. The latter relay upon energizing connects ground at armature 235 to the lower winding of the line relay 206 so that the line relay may be maintained energized by a bridge at the repeater E.

Referring now to the repeater E, the relay 104 is energized from ground at armature 114 but is slow to pull up so as to allow time for operating the line relay at the cord circuit O over the upper talking conductor as explained. On energizing, relay 104 disconnects ground from the conductor 130 and the initial energizing circuit of the line relay 206 of the cord circuit O. At armature 120 and its working contact, relay 104 connects ground to the release trunk conductor 77; at armature 121 and its working contact closes a circuit through the polarizing winding of the electro polarized relay 105; and at armature 118 and its working contact completes a bridge across the trunk conductors 130 and 131 which may be traced over the following path: conductor 130, armature 113 and its working contact, working contacts of armature 118 and said armature, armature 116 and its resting contact, lower winding of the elec-

tro-polarized relay 105, normally closed springs controlled by armature 108 of relay 100, right hand winding of the impedance coil 106, and working contact of armature 111 and said armature to conductor 131. By the closure of this bridge across the trunk line a circuit is completed for maintaining energized the double wound line relay 206 of the cord circuit O.

When the line and release relays of cord circuit O are operated, as above explained, the latter relay at armature 232 opens a point in the circuit of the supervisory lamp SL and at its working contact connects ground to conductor 257. At armature 233, relay 205 prepares a point in the impulsing circuit; at armature 235 and its working contact connects ground to the lower winding of the line relay 206 as previously explained.

It may well be mentioned at this point that the register selector C' is a preselecting switch, and it is assumed that the switch C' has preselected the register set shown in the drawings in Fig. 3. The method of preselecting an idle register set will be fully described hereinafter. When relay 205 pulls up it closes at armature 234 an energizing circuit for relay 204 as follows: from ground by way of armature 224 and its resting contact, lower winding of relay 204, working contact of armature 234 and said armature, armature 222 and its resting contact, resting contact of armature 218 and said armature, conductor 301, wiper 301', bank contact connected to terminal pin 305, jumper 308, terminal contact 311, conductor 372, armature 331 and its resting contact, terminal 379, jumper 380, terminal 381, armature 334 and its resting contact, and winding of relay 325 to battery.

When the above traced circuit for relay 325 is closed, said relay energizes and at armature 338 and its resting contact opens a normally closed short circuit from around the relay 323, at armature 339 and its working contact closes a circuit for operating the time switch P, and at armature 340 and its resting contact opens one of the several energizing circuits for the relay 392.

Returning now to the cord circuit O, relay 204 is energized over the previously traced circuit and at armature 227 and its working contact prepares a point in the circuit for the call lamp CL, at armature 228 and its working contact prepares a circuit for relay 201, at armature 230 and its working contact closes a locking circuit for itself through armatures 220 and 217 to grounded conductor 257, and at armature 231 and its working contact connects direct ground to the release trunk conductor 301 to guard the seized register set from being seized by other register selectors such as C'. At armature 229 and its resting contact, relay 204 opens a point in the circuit for the busy relay 202, so

that when impulsing is started the busy relay will not be energized from ground at armature 236, and at its working contact prepares the impulsing circuit extending over conductor 303 to the register set.

Everything is now in readiness for the transmission of the second series of impulses. The subscriber will now operate his calling device in accordance with the digit 3, which 10 will cause line relay 101 of the repeater E to fall back a corresponding number of times, which results in the operation of slow relay 103 for placing a direct bridge across the trunk conductors 130 and 131. The operation 15 of line relay 101 causes the circuit of the line relay 206 to be interrupted a like number of times. Each time line relay 206 falls back an impulse is transmitted to stepping magnet 461 over the following circuit: 20 ground, armature 236 and its resting contact, working contact of armature 233 and said armature, armature 229 and its working contact, impulse conductor 303, wiper 303', Fig. 3, bank contact engaged by wiper 303', terminal pin 306, jumper 309, terminal contact 312, conductor 371, winding of relay 327, wiper 355 of the register control switch RCS, conductor 360, stepping magnet 461 of the register switch R¹ to battery. By the operation 25 of the stepping magnet 461 wiper 464 of the register switch R¹ is advanced three steps and is brought to rest in engagement with the third contact of its bank. The slow acting relay 327 is energized in series with stepping magnet 461 and retains its armature 344 attracted while the said magnet is being operated. In operated position, relay 327 closes 30 a circuit for the slow acting relay 328, which is held in operated position also during the operation of the first register switch. After 35 the last impulse has been transmitted, the slow-acting relay 327 will deenergize and break the circuit of relay 328 at armature 344. Since the latter relay is slow-acting, however, a circuit will be closed for an instant which extends from the grounded armature 344 by way of its resting contact, working contact of armature 345 and said armature, and the winding of stepping magnet 359 of the register control switch RCS 40 to battery. One impulse is thus transmitted to the stepping magnet 359, and the wipers 355 and 356 are advanced one step into engagement with the second contacts in their respective banks. The advance of wiper 356 is of no effect, but when wiper 355 moves from its first contact to the second, the operating circuit is thus transferred to conductor 361 which extends to the stepping magnet 441 of the register switch R².

It may well be mentioned at this time that relay 323 was energized as soon as the register switch R' moved off-normal. The circuit for relay 323 may be traced as follows: 45 from ground thru low resistance winding of

relay 322, winding of high resistance relay 323 conductor 405, off-normal springs 463, winding of release magnet 462 to battery. The relay 322 and release magnet 462 are not energized in this circuit on account of the high resistance of relay 323. At armature 364, relay 323 removes ground from conductor 376 and prepares a circuit for relay 324 at its working contact. Relay 324 however does not energize at this time on account of the ground connection at armature 231, Fig. 2, extending over conductor 301.

The calling subscriber will now operate his calling device in accordance with the next digit in the desired number. As a result, the line relay 206 in the cord circuit operates the same as before, but now sends four impulses over the operating circuit to the stepping magnet 441 of the register switch R². The stepping magnet 441 is thus operated to advance its wipers 444 four steps and the wiper is brought to rest in engagement with the fourth contact in its banks.

The slow acting relays 327 and 328 are energized during the transmission of the second series of impulses the same as during the first, and when the impulses cease another impulse of current is transmitted to the stepping magnet 359 of the register control switch RCS, thus advancing the wipers 355 and 356 another step, and transferring the operating circuit by way of conductor 362 to the stepping magnet 421 of the register switch R³.

It will not be necessary to consider in detail the manner in which the register switches R³ and R⁴ are operated. When the digit 5 is called a series of five impulses are transmitted to the stepping magnet 421 of the register switch R³ and the wiper 424 is advanced into engagement with the fifth contact in its bank. At the end of the series of impulses, the register controlled switch is operated one step and the operating circuit is transferred by way of conductor 363 to the stepping magnet 401 of the register switch R⁴. The series of six impulses which results from the calling of the final digit thus causes the operation of the stepping magnet 401 and the wiper 404 is advanced into engagement with the sixth contact in its bank. The stepping magnet 359 of the register control switch is given another impulse of current also at the end of the last series of impulses and wipers 355 and 356 are advanced one more step.

By the last operation of the register control switch RCS wiper 356 is brought into engagement with the fifth contact in its bank and ground is placed on conductor 369, resulting in the energization of relay 326. Upon attracting its armature 342, relay 326 stops the operation of the timing switch P, while at armature 341 ground is connected by way of armature 330 for lighting the set-up 130

lamp 370 thereby indicating to an operator that a call has been set up on the third register set. Relay 326 at armature 343 and its resting contact removes a short circuit from around the relay 329 and at its working contact closes a circuit over the conductor 377 for energizing the relay 281 of the switch CCS in Fig. 2. Armature 343 also removes ground from conductor 376 thereby removing ground from the bank contact in the switch CCS which corresponds to the register set shown in Fig. 3.

The consecution switch CCS has all its bank contacts normally grounded over conductors such as conductor 376 and as soon as relays such as relays 326 and 323 are energized ground is removed from the bank contact corresponding to the register set in use.

20 Responsive to the energization of relay 281 over the above traced circuit, said relay at armature 282 and its working contact closes a circuit for operating the stepping magnet 283 by way of the grounded bank contacts 25 of the consecution switch CCS. The stepping magnet 283 energizes from ground on the grounded bank contacts encountered by wiper 280, interrupts its own circuit, and continues to operate in a buzzerlike manner 30 until the wiper 280 encounters the bank contact connected to conductor 376 from which ground has been previously removed. Responsive to the wiper 280 coming into engagement with the bank contact connected to conductor 376, a circuit is no longer closed for the stepping magnet and a circuit may now be traced for energizing the high resistance relay 329 Fig. 3, as follows: from ground winding of relay 329, armature 332 and its resting contact, conductor 378, conductor 376, bank contact individual to the register set shown in Fig. 3, wiper 280, working contact of armature 282 and said armature, interrupter springs of the stepping magnet 283, and winding of stepping magnet 283 to battery. Due to the high resistance of relay 329 the stepping magnet 283 is not energized over the above traced circuit. Relay 329, however, is energized and at armature 353 connects ground to conductor 373 for lighting the call lamp CL over a circuit as follows: from ground, working contact of armature 353 and said armature, conductor 373, terminal 313, jumper 310, terminal 307, bank contact of the register selector C', wiper 304', conductor 304, armature 227 and its working contact, winding of relay 211, resting contact of armature 219 and said armature, armature 244 and its resting contact, call lamp CL to battery. Relay 211 is energized over the above traced circuit and at armature 248 disconnects the supervisory lamp SL. Other calls may be registered on the other register sets at any time now and when the registration is completed the set-up-pilot lamps, such

as lamp 370, corresponding to the register sets in use will be lighted, but this has no effect on the consecution switch CCS, which makes no further movement until the call on the third register set has been disposed of.

70 Relay 329 is the relay which switches over the registered call to the lamps of the indicating device and the manner in which this is done will now be pointed out, it being recollected that the wipers 464, 444, 424 and 404, are now resting on the 3rd, 4th, 5th, and 6th contacts in their respective banks. When the armatures 348 of relay 329 are operated, ground is connected to conductors 349 to 352, inclusive. It follows, therefore, that with the conductors 349 to 352, inclusive, grounded the conductors 476, 455, 343, and 413 will also be grounded. These latter mentioned conductors extend to the indicating device V and terminate in the #3 lamp of the first group, the #4 lamp of the second group, the #5 lamp at the third group, and the #6 lamp in the fourth group, respectively. The other side of the lamp is connected to battery and the lamps mentioned are accordingly illuminated.

75 The manner in which the operator handles the call thus displayed before her will now be considered. When the relay 329 in Fig. 3 pulls up and closes the circuit for displaying the registered number to the operator, it also closes at its armature 353 the circuit for the call lamp CL in the cord circuit O. The lighting of the lamp CL which is individual to the cord circuit O is 80 lighted simultaneously with the lamps in the indicating device V, thus enabling the operator to know which one of the cord circuits is being used by the automatic subscriber, whose wanted number is at this particular time being shown on the indicating device. Having observed the #3456 and knowing by the lighting of the called lamp CL that the cord circuit O is the one in use, the operator will test the multiple jack of the line 3456 with the tip of her plug in the usual manner in order to find out whether or not the line is busy. If the line is 85 found to be in use, the operator will hear the well known busy click, and will immediately operate her busy key BK. The two keys indicated by BK are in reality one key and have been shown as two keys so as to simplify the drawings. By the operation of the upper busy key BK the stepping magnet 283 of the consecution control switch CCS is 90 energized. A circuit is also closed through the lower busy key BK from ground at said key, through working contact of armature 242 of relay 209 which was previously energized in parallel with relay 211, armature 243 and its resting contact, winding of relay 202 to battery. Relay 202, immediately 95 energizes and locks itself at armature 221 to the grounded conductor 257. Relay 202 at 100

105

110

115

120

125

130

armature 220 opens the locking circuit of relay 204 which thereupon deenergizes, at armature 222 removes ground from the release trunk conductor 301, and at armature 5 223 and its working contact connects the busy tone thru the condenser 259, through the lower right hand winding of relay 208 to battery. The busy tone is now transmitted to the calling subscriber in the well known manner and need not be explained in detail.

10 By the removal of ground from the release trunk conductor 301, the short circuit around relay 324 has been removed, and said relay energizes over a circuit from ground at armature 364 in series with relay 325. Relay 15 324 upon energizing closes at armature 336 and its working contact a circuit for releasing the register control switch, the time switch T, and all of the register switches R¹ to R⁴ inclusive, as follows: ground through 20 the low resistance winding of relay 322, armature 336 and its working contact, off normal springs 357 of the register control switch RCS, release magnet 358 to battery; to the resting contact of armature 347 and said armature, off normal springs 367 of the time switch T, release magnet 366 to battery; to conductor 405 from which point ground is connected to the release magnets 25 402, 422, 442 and 462 through off-normal contacts 403, 423, 443 and 463, respectively. The register control switch RCS, the time switch T, and the register switches R¹ to R⁴, inclusive, release in the well known manner. Relay 322 is energized in series with the various release magnets and at armature 334 and its working contact connects ground to the conductor 372 thereby rendering the register set busy until the apparatus in the 30 set has been completely restored to normal. When relay 324 operates its armature 336, relay 323 is short circuited and after an interval, said relay deenergizes. Relay 323 upon deenergizing opens at armature 364 35 the circuit of relays 324 and 325 which thereupon deenergize. At armature 364 and its resting contact, relay 323 connects ground to conductor 376 so as to busy the register set in the consecution control switch. Relay 325 deenergizes before relay 324 thereby 40 maintaining at armature 338 the short circuit around relay 323. As soon as all of the register switches, the register control switch and the time switch T have been returned to 45 normal, the circuit of relay 322 is opened at the various off normal contacts. In case any one of the above switches did not properly release, relay 322 would be maintained energized, thereby maintaining the register set 50 busy. The relay 326 was also deenergized responsive to the release of the register control switch thereby causing relay 281 of the switch CCS to deenergize. Relay 329 is again short circuited and said relay releases 55 and disconnects ground from conductors 349

to 352, inclusive. All of the apparatus shown in Figs. 3 and 4, have been returned to their normal positions, and are available for use in another call.

When the operator releases the busy key 70 BK, the stepping magnet 283 of the consecution control switch CCS deenergizes and advances the wiper 280 one step.

The reason for holding stepping magnet 283 energized during the time the busy key 75 is depressed is to prevent the operation of the switch CCS thereby preventing the operation of busy relays in other cord circuits when calls on the other cord circuits are waiting to be displayed.

Assuming however, that the line is found to be idle, the operator will at once insert the plug P into the jack of the wanted line, which in the present case is the jack J. As soon as the plug is inserted into the jack, a circuit is 80 completed for the sleeve relay 210 in series with the cut-off relay 261 of the called line, and the latter relay is energized to clear the line of its normal battery and ground connections in the usual manner. Relay 210 is energized also and at armature 240 prepares a circuit for the supervisory lamp SL, at armature 241 opens the circuit of relay 209 at its resting contact and at its working contact closes a circuit for energizing relay 201, 85 at armature 243 and its resting contact opens the circuit of the busy relay 202, at armature 244 and its resting contact opens the circuit of the call lamp CL, at armature 245 and its working contact connects ground to conductor 279, at armatures 246 and 247 and their working contacts completes a ring back circuit for transmitting ringing induction to the calling subscriber, at armature 247 and its working contact connects generator to the 90 called line, and at the resting contact of armature 247 disconnects the operator's headset. Ringing current is now connected to the called subscriber over the following path: from generator, winding of relay 212, resting 95 contact of armature 256 and said armature, working contact of armature 247 and said armature, tip of plug P, tip of jack J through the called subscriber's ringers, back over the ring conductor of plug P, armature 250 and 100 its resting contact, resistance 259, to battery. 105

When the sleeve relay was energized it closed a circuit for energizing relay 201 as follows: grounded conductor 304, armature 227 and its working contact, armature 241 and its 110 working contact, working contact of armature 228 and said armature, normally closed springs controlled by armature 217, and winding of relay 201 to battery. Relay 201, 115 upon energizing, closes a locking circuit for itself at armature 217 and its working contact, and at armature 217 and its resting contact opens the locking circuit of relay 204. At armature 218, relay 201 disconnects ground 120 from the release trunk conductor 301, and at 125 130

armature 219 prepares a substitute circuit for the call lamp CL which includes the interrupter I for flashing the call lamp CL in case the operator removes the plug P from the jack 6 prematurely.

Responsive to the removal of ground from the conductor 301 the short circuit around relay 324 is removed and said relay energizes in series with relay 325. The operation of the 10 relay 322 and the release magnets of the various switches in Figs. 3 and 4 are now the same as previously described and the apparatus is restored to normal. The register control switch, the register switches, and the consecutive control switch are now in readiness 15 to be used for another call.

Referring now to the cord circuit O, it has been explained how the connection has been completed to the line of the called station 20 A', and how ringing current is projected over the called line to signal the subscriber. During the ringing operation a tone is induced in the lower right hand winding of the repeating coil of the cord 25 circuit O by means of which the calling subscriber is advised that the called subscriber is being signalled. When the called subscriber answers, the ring cut-off relay 212 energizes in a well known manner and closes 30 a circuit at armature 249 for relay 213 from ground over the sleeve of plug P and jack J. Relay 213, upon energizing, at armature 251 completes a locking circuit for itself and at armatures 250 and 256 and their resting 35 contacts disconnects the generator from the called line and at their working contacts connects the line of the called subscriber to the right hand windings of the repeating coil thereby completing a talking circuit 40 for the called subscriber which includes the lower and upper windings of relay 208 and the right hand windings of the repeating coil. Relay 208 is energized over the called subscriber's loop and at armature 239 45 completes an energizing circuit for the reversing relay 207. In energized position, relay 207 reverses the trunk conductors 130 and 131 as regards their connections with the windings of the line relay 206, and the 50 direction of current flow in the trunk line is thus reversed. Due to the reversal of current flow in the trunk line the polarized relay 105 in the repeater E is now energized and at armature 119 and its working contact 55 completes a circuit for energizing the reversing relay 100 of the repeater E. Upon energizing relay 100 reverses the trunk conductor 76 and 78 as regards their connections with the winding of the line relay 101, and the direction of current flow in the calling 60 line is thus reversed. This operation may be used for operating a meter or for similar purposes, and is provided in accordance with standard practice, although it is

of no utility in the particular system shown herein.

The required connection having been established, the subscribers may now converse as desired. When the conversation is finished both subscribers will hang up their receivers, and the replacement of the receiver at the calling station A causes the de-energization of the line relay 101 in the repeater E and also the release of slow acting release relay 102. Relay 101 upon releasing, completes a circuit for relay 103 so that when relay 102 deenergizes, ground is removed from release conductor 77 thereby allowing the automatic switches to be restored to normal in the usual manner. The bridge across the trunk conductors 130 and 131 being broken by the deenergization of line relay 101 of the repeater E the circuit of the line relay 206 in the cord circuit O is thereby opened whereupon said relay deenergizes. After a short interval of time the slow acting relay 205 also deenergizes and closes a circuit for the supervisory lamp SL at armature 232, and at the same 80 armature also opens the circuit of relays 207 and 201 which thereupon deenergize. Relay 205 also removes ground from conductor 279 and prepares a circuit for relay 203. When the slow-acting relay 102 of the repeater E deenergizes it opens at armature 114 a circuit for relay 104 and at the same armature by way of its resting contact substitutes another circuit for energizing relay 104 as follows: from ground by way of armature 245 and its working contact, conductor 279 lower winding of line relay 206, normally closed springs controlled by armature 238, lower left hand winding of the repeating coil, resting contact of armature 216 and said armature, conductor 131, resting contact of armature 114, and winding of relay 104 to battery. Relay 104 energizes over the above traced circuit but due to its high resistance, the line relay 206 is not energized. At armature 120, relay 104 connects ground to the release conductor 77 thereby maintaining this trunk circuit busy to the automatic switches in the automatic office as long as the plug P remains inserted in the jack J. 100

The automatic switches now have been released, a disconnect signal has been given to the operator, and the trunk line in use has been made busy pending the pulling down of the connection. When the operator observes the lighted supervisory lamp SL she will remove the plug of the cord circuit O from the jack and relays 210 and 213 are deenergized and restored to normal. By the falling back of relay 210 the circuit of the supervisory lamp SL is broken at armature 240 and at armature 245 ground is removed from conductor 279 thereby permitting the relay 104 of the repeater E to deenergize and remove ground from the release trunk 110 120 125 130

conductor 77. All the apparatus has now been restored and is ready for use in handling another call.

Certain details of the system will now be explained which it was not convenient to go into before, and the first thing which will be considered is the preselecting operation of the register selector C'. For this purpose, it will be assumed that the cord circuit O is idle, that the wipers of the register selector switch C' are standing in the position shown in the drawing, Fig. 3, and that the register set associated with these bank contacts becomes busy. Under the above conditions a circuit 5 can now be traced to the lower winding of the differential relay 203 of the cord circuit O over the following path: from ground on the bank contact associated with the busy register set, wiper 301', armature 218 and its 10 resting contact, resting contact of armatures 222 and said armature, armature 234 and its resting contact, and lower winding of relay 203 to battery. Relay 203 energizes over the 15 above traced circuit and at armature 225 maintains the above traced circuit independent of armature 234 so that if the cord circuit should be taken into use, the circuit of the relay 203 would not be opened by the 20 operation of the release relay 205. At armature 224 and its resting contact, relay 203 opens the energizing circuit for relay 204 so that relay 204 cannot energize until after 25 an idle register set has been selected. In addition to the above, relay 203 at armature 30 224 and its working contact connects ground to conductor 302 thereby closing a circuit for the stepping magnet 320 of the register selector C' so that said stepping magnet will operate in a manner of a buzzer until ground 35 is removed from conductor 302. Although relay 203 is a differential relay the resistance inserted in series with the upper winding will not permit the relay to be deenergized when armature 224 connects ground to the upper 40 winding of said relay. As long as the wiper 301' encounters grounded contacts of busy register sets, relay 203 will be maintained 45 energized through its lower winding. It will now be assumed that an idle register set is 50 reached and when the test wiper 301' engages the bank contact associated therewith, said contact will not be grounded, but will have a battery potential thereon. Under this condition the circuit to the lower winding of relay 203 is opened. Due to the current flow 55 through the upper winding of relay 203, magnetic flux will be built up in opposition to the magnetic flux created by the circuit through the lower winding and when the flux reaches a certain point said relay is quickly 60 deenergized, thereby removing ground from conductor 302 and stopping the operation of the register selector on the idle register set.

In case the cord circuit O should be seized 65 and the calling subscriber should start di-

alling before an idle register set has been seized the busy relay 202 would be energized for transmitting a busy tone to the calling subscriber.

The circuit for energizing relay 202 may be traced as follows: ground from armature 236 and its resting contact, working contact of armature 233 and said armature, armature 229 and its resting contact, armature 243 and its resting contact, and winding of busy relay 202 to battery. 70

Another feature of the invention which is more or less related to the foregoing is the novel means by which the automatic trunk, which is associated with the cord circuit O, is made busy during the time the register selector is hunting for an idle register set. It will be remembered that relay 203 was energized to control the hunting operation of the register selector. Relay 203 upon energizing, at armature 226 connects ground to conductor 279 from whence it extends by way of the lower winding of the line relay 206, normally closed springs controlled by armature 238, lower left hand winding of the repeating coil, resting contact of armature 216 and said armature, conductor 131, resting contact of armature 114 and said armature, and winding of relay 104 to battery. The line relay 206 in the cord circuit is not energized over this circuit on account of the high resistance of relay 104 but the latter relay, however, energizes and at armature 120 connects ground to the release trunk conductor 77 thereby rendering the repeater E busy to 85 automatic subscribers. 90

Another feature of the invention relates to the function of the timing switch P, Fig. 3, which releases each time a digit is dialled. This switch is provided for the purpose of handling the so called mutilated calls, which are calls arriving at a register set which, because of improper dialling by the calling subscriber, or failure of some switch to function properly are not completely registered. It will be understood that in the ordinary operation of the system, a call is displayed to the operator by the energization of relay 329 at the proper time under control of the consecutive control switch CCS. The energization of relay 329, however, is contingent on four series of impulses being transmitted through the register control switch RCS, which causes the wiper 356 to engage the fifth contact in its bank to ground conductor 369; and it will be appreciated, therefore, that if less than four digits are registered, relay 329 will not ordinarily energize, and the partially registered number will never be displayed to the operator. Experience has shown that these incompletely registered calls are a fruitful source of trouble, since each such call, occupies a register set until the calling subscriber hangs up his receiver, without giving the operator a signal at any time. In order to eliminate the 100 105 110 115 120 125 130

difficulty pointed out, the timing switch P is provided, and this switch is adapted to bring about the display of any call after a certain time interval, regardless of whether all of the digits in the called number are registered or not. It will now be assumed that a call has arrived at the register set shown in Figs. 3 and 4 and that relay 325 has been energized. When relay 325 pulls up a circuit is closed for the stepping magnet 365 of the timing switch P at armature 339, and the timing switch begins to operate under control of a time control impulse sender, indicated by the reference character T. This impulse sending mechanism is so arranged, that the conductors 375 are grounded at one second intervals with the result that after the expiration of ten seconds the wiper 368 closes a circuit by which ground is connected to conductor 369. This causes relay 326 to be energized, which removes ground from conductor 376 thereby controlling the consecution control switch CCS and incidentally the relay 329 so that whatever digits, if any, have been registered, are displayed to the operator. It will be remembered that relay 328 is operated once for each series of impulses and said relay at armature 346 opens the circuit of the stepping magnet 365, and at armature 347 closes a circuit to the release magnet 366. The timing switch P is, therefore, released each time a digit is dialled by a calling subscriber and therefore it would be ten seconds after the last digit had been dialled by the calling subscriber before the time switch P would complete the circuit for relay 326. It is intended that the mutilated calls will be extended by the operator to a complaint or trouble operator by plugging into a trunk line provided for this purpose in order that the regular operator may be free to confine her attention to handling the regular traffic.

Another novel feature of the invention which relates to the foregoing is the circuit arrangements by means of which the ringing current is cut off and a ring back tone given to the calling subscriber when a calling subscriber is connected by means of the cord circuit to the information and complaint operator's trunk circuit such as illustrated at TC Fig. 2. Assuming that only a partially registered call has been displayed to the operator and that the cord circuit O is the cord circuit over which the calling party is endeavoring to establish a connection, the operator will insert the plug P into the jack J' which is used for handling special calls of this nature. Responsive to the insertion of the plug P into the jack J' a circuit is closed for energizing relay 210 of the cord circuit O and relay 266 of the operator's trunk circuit TC in series over the sleeve of the jack J'. As soon as relay 210 is energized a circuit may be traced for energizing the ring cut-off relay 212 as follows: from battery through

the right hand winding of induction coil IC, common conductor 270, working contact of armature 268 and said armature, conductor 271, tip of plug P, armature 247 and its working contact, armature 256 and its resting contact, and winding of relay 212 to generator. Relay 212 is energized over the above traced circuit and closes a circuit for operating relay 213 as previously described. Ringing current is thus cut off. It will be noted, that interrupted generator is connected to the left hand winding of the induction coil IC and therefore a circuit may be traced through the left hand winding of induction coil IC over the previously traced circuit to armature 247 from where it extends to armature 246 and its working contact, condenser 259, lower right hand winding of repeating coil, and lower winding of relay 208 to battery. Ringing induction is now transmitted to the calling subscriber through the windings of the repeating coil in the well known manner. When relay 266 in the trunk circuit TC is operated, it closes a circuit for lighting the call lamp L, thereby notifying the trunk operator that a call should be answered. The operator upon observing the lighting of the lamp L operates her answer key AK thereby connecting her headset to the trunk conductors 271 and 272. The key AK also closes a circuit for energizing relay 265 which opens the circuit for the lamp L at its upper armature and at armature 268 also opens the ring-back tone to the calling subscriber. The information and complaint operator may now converse with the calling subscriber in the usual manner and take the necessary steps to either complete the call or inform the calling subscriber of his error. It can be plainly seen from the foregoing that the same circuit which cuts off the ringing current also applies the ringback tone to the cord circuit O for transmitting the tone to the calling party.

Another feature of the invention relates to the method of multiplying the register sets, which are only eight in number, to the register selector banks. The multiplying of the register sets in the banks of the register selectors is accomplished by the aid of an intermediate distributing frame. The banks of all the register selectors at the position are connected in multiple and a cable connects the multiply connected banks with one side of the distributing frame, where the cable is terminated on twenty-five sets of terminal pins.

In the bottom half of Fig. 4, the distributing frame is indicated by the reference characters I. D. F. The lower row of twenty-five terminals are the terminals for the release trunk conductors coming from the bank contacts of the register selectors. The release trunk conductors of the eight register sets are connected to eight terminal contacts on the other side of the I. D. F. Although only the

release trunk terminals are shown, it will be understood that there are three terminals to each set. As the register selectors have access to only eight register sets the terminal pins are divided into three groups, the first group comprising terminal pins 1 to 8, inclusive, the second group 9 to 16, inclusive, and the third group 17 to 25, inclusive. The eight register sets are cross connected by jumpers at the I. D. F., to the terminal pins numbered 1 to 25, inclusive. The number 1 register set is multiplied to the #1, #13, and #19 terminal pins, the number 2 register set is multiplied to the #2, #9 and #22 terminal pins, the number 3 register set is multiplied to the #3, #14, and #17 terminal pins, the number 4 register set is multiplied to the #4, #10, and #20 terminal pins, the number 5 register set is multiplied to the #5, #15, and #23 terminal pins, the #6 register set is multiplied to the #6, #11, and #18 terminal pins, the number 7 register set is multiplied to the #7 and #21 terminal pins, and the number 8 register is multiplied to the #12 and #24 terminal pins. The eighth, sixteenth, and twenty-fifth terminal pins are dead and are cross connected in such a manner that they provide stopping positions for the register selectors in case all eight register sets become busy. With the register sets multiplied at the I. D. F., in the manner pointed out it necessarily follows that each of the register sets is accessible to a register selector at a plurality of points in its bank. Although the corresponding bank contacts of all the register selectors at the position are connected in a straight multiple, the cross connections at the I. D. F. divides each bank into a plurality of groups of bank contacts and provides a slip between the bank contacts in each of the groups. Considerable saving is effected by multiplying the register sets at the I. D. F., because it permits changes such as varying the number of register sets to be used or for varying the slip in the multiple between bank contacts to be readily and easily made at the same time keeping the multiples straight between banks.

The slip in the register selector bank contacts between groups is provided for the purpose of preventing all the idle preselecting register selectors from preselecting the same idle register set on their next operation in case they had previously selected the same register set. For example, it will be assumed that there is a register selector in engagement with the multiples of the first register set of the different groups that is, a first register selector is in engagement with the #1 bank contact in the first group of its associated bank, a second register selector is in engagement with the #13 bank contact in the second group of its associated bank, and a third register selector is in engagement with the #19 bank contact in the third group of its associated bank.

Assuming now that the #1 register set becomes busy, ground is connected to the multiples of said set causing all of the register selectors which are in engagement therewith to start hunting to pre-select another idle register set. The said first register selector will step one step into engagement with the 2nd bank contact or the multiples of the #2 register set, the said second register selector will step one step into engagement with the 14th bank contact or the multiples of the #3 register set, and the said third selector will step one step into engagement with the 20th bank contact or the multiples of the #4 register set. It can be seen from the foregoing that each register selector, which have their wipers positioned in different groups, selects a different register set for each corresponding step when they are initially started from multiples of the same register set. 70 75 80 85

Having explained in detail how the bank contacts of the register selectors are connected in a slip multiple by means of jumpers at the I. D. F., when eight register sets are to be used, I will now briefly point out how the bank contacts of the register selectors are cross-connected to the register sets at the I. D. F., when a variable number of register sets is to be used at an operator's position. 90 95

The following is a chart showing the slip multiple arrangement for cross-connecting the bank contacts of the register selectors at the I. D. F., to the register sets:—

Chart				
Register sel. Bank Contact No. —	8 Reg. sets No. —	7 Reg. sets	6 Reg. sets	5 Reg. sets
1	1	1	1	1

100 110 115 120 125 130

Reading from left to right, the left hand column indicates the numbers of the register selector bank contacts which are connected to correspondingly numbered terminal pins on the I. D. F., and the other columns indicate the number of the register sets which are multiplied to the selector bank contacts in the following manner. In order to explain the chart it will be assumed that only six register sets are to be used at an operator's posi-

tion and therefore only the first and fourth columns may be considered. The #1 bank contact is multiplied to the #1 register, the #2 bank contact to the #2 register set, the #3 bank contact to the #3 register set, the #4 bank contact to #4 register set, the #5 bank contact to the #5 register set, and the #6 bank contact is connected to a dead terminal pin. In the next group of bank contacts the #7 bank contact is multiplied to the #2 register set, the #8 bank contact to the #4 register set, the #9 bank contact to the #6 register set, etc. In case 5 or 7 register sets were to be used at an operator's position, the register sets would be cross-connected at the I. D. F., in an obvious manner. It can plainly be seen from the foregoing that in order to change the number of register sets to be used or in order to change the slip multiple it is only necessary to change the cross connections or jumpers at the I. D. F.

There are provided in the instant case eight register sets per operator's position. Seven of which are normally available for use while the eighth is artificially made busy. According to another feature of the invention when all seven register sets become busy, a circuit will be completed for energizing the all trunk busy relay ATB to busy the operator's position. A still further feature of the invention which may be described in conjunction with the preceding, relates to the means for rendering the eighth register set idle so that if a call should come into the operator's position before said position has been made busy, the call would seize the eighth register set and the connection would be completed in the same manner as previously described.

Referring now to Fig. 3, the first seven register sets have their terminals 379 and 381 connected by a jumper 380 and have their armatures 340 connected by a conductor such as 386 to terminal 387. All of the terminals 387 are connected to a common conductor which extends to the relay 392. The eighth register set, or the register set normally held in reserve, is connected in the following manner: the jumper, such as jumper 380, is cut and the terminal 379 is connected to terminal 383 and the terminal 381 is connected to the terminal 382. At armature 340 the conductor such as conductors 386 is moved from terminal 387 to terminal 388 which in turn is connected to an individual conductor 390 for controlling the relay 391.

It will now be assumed that the first seven registers are busy and under such conditions ground at the various seven register sets have been disconnected from the common conductor 389, thereby permitting relay 392 to de-energize. Relay 392, upon deenergizing, removes ground from armature 396 thereby rendering the eighth register set selectable. At armature 397 and its resting contact, relay 392 prepares a circuit for relay 393. At

armature 398 and its resting contact, relay 392 connects ground to conductor 399 for energizing the all trunk busy relay ATB Fig. 2. Relay ATB, upon energizing, connects ground to the lower winding of all line relays such as 206 at the operator's position. The ground connections to the lower winding of the line relays extend over the conductors 131 causing the energization of the relays 104 as previously explained. The latter relays, upon energizing, connect ground potentials to armatures 120 thereby rendering the outgoing trunks extending to the operator's position busy.

It will now be assumed that a call has come in during the interval in which the last of the seven register sets was seized and the trunks extending to the operator's position were made busy. Under this condition such a call would operate the register selector such as C' to cease the eighth register set. The call would then be completed in the same manner as previously described. However, as soon as the eighth register set is seized, the circuit for relay 391 will be opened due to the removal of ground from conductor 390 whereupon said relay will deenergize and close a circuit for operating relay 393. At armature 394 relay 391 closes a shunt around the armature 396 so that if one of the first seven register sets becomes idle the operation of relay 392 will not interfere in any way with the call being set up on the eighth register set. When relay 393 is energized over the above traced circuit said relay removes ground from conductors 406 and the dead contacts in the terminal block on the I. D. F., Fig. 4, thereby providing a plurality of stopping positions for the idle register selectors when all eight register sets are busy. As soon as one register set becomes idle the circuit of relay 393 is broken and ground is again applied to the dead contacts.

Circuit arrangements have been made so that an operator can busy the incoming trunks at her position in groups of eight by means of a plurality of keys such as key TK, Fig. 2. It being understood that the trunk lines terminating on a trunk key, such as TK, come from different automatic exchanges or from different groups so that by the operation of only one or more keys all of the trunk lines from one particular office or group would not be made busy. By the aid of what is known as positon linking keys an operator at a position may connect her headset to either position on either side of her. A position linking key for position 1 is shown in the dotted rectangle directly below POS. 1, below POS. 2 is shown the position linking key for position 2, or for the position with which the cord circuit O is associated, and in the dotted rectangle below POS. 3 is shown a position linking key for position 3. By operating a certain plurality of keys TK at posi-

tion 1 the left half of said position is made busy, the right half of position 3 is made busy in a similar manner. The operator at position 2 will then operate the position linking keys at positions 1 and 2 thereby connecting her headset to the cord circuits at positions 1 and 3 as well as position 2 so that she may complete calls coming into such positions during light traffic loads.

10 A description will now be given of the means by which the trunks extending from an automatic exchange to an operator's position at the manual exchange are made busy when the main battery fuse at such position blows. In the upper left hand corner of Fig. 2 there is illustrated the bus-bar to which the main battery is directly connected. The conductor 273 illustrates the fuse wire by means of which the main battery is connected 15 to the lower bus-bar and the conductor 274 illustrates the means by which all of the apparatus at the operator's position is connected to main battery, it being understood that all of the battery symbols shown at the 20 various relays and etc., are diagrammatic, while in reality they all extend to the conductor 274. In case the fuse 273 should blow out for some reason or other, the spring connected to the upper bus-bar will spring into 25 contact with the alarm bus-bar 276 thereby connecting main battery to conductor 275 which closes energizing circuits to all the upper windings of the relays such as relay 200. The relays 200 are accordingly energized and at armatures 214 and 216 disconnect the conductors 130 and 131 from the 30 cord circuits and at armatures 216 and their working contacts connect ground to the trunk conductors 131 for energizing the relays 104 in the repeaters E. The relays 104 energize and busies all repeaters E to selector switches having access thereto in the 35 same manner as previously described.

At the extreme left of Fig. 2, there is 40 shown a test jack by means of which a test man may plug into cord circuit O for testing purposes or for completing a call to a particular subscriber. When the test man plugs 45 into the test jack, the relay 200 is energized over its lower winding and said relay busies the repeater E in the same manner as previously described. The test man may now dial up the register switches in the same manner as the calling subscriber. In Fig. 3, 50 there is also shown a test jack by means of which a test man may routine the register set. When the test man plugs into the test jack, relay 321 is energized and said relay at armature 330 disconnects the set up pilot 55 lamps, at armature 331 connects ground to conductor 372 for making the register set busy, at armature 332 opens the circuit of relay 329, and at armature 333 removes one of the ground connections from the common 60 conductor 389. The test man has special 65

test equipment by means of which the register set may be tested. It will be observed that with the aid of these test jacks the test man can plug into the cord circuit O or the register sets at the same time the operator's position is in use without interfering with calls at this position.

Having described my invention, what I consider to be new and desire to have protected by Letters Patent will be pointed out 70 in the appended claims:

What is claimed is:

1. In a telephone system, trunk lines comprising only two talking conductors extending from an automatic to a manual exchange, a relay in each of said trunk lines at the automatic exchange for making its associated trunk line busy when energized over a circuit including only one of the talking conductors of its associated trunk line, and means including a second relay common to said trunk lines at the manual exchange operable automatically to cause the energization of all said first relays of the trunk lines which are not in use.

2. In a telephone system, an automatic exchange, a manual exchange, trunk lines comprising only two conductors extending from said automatic to said manual exchange, and means associated with each of said trunk lines at the automatic exchange and controlled over only one of its associated conductors for making each of said trunk lines which are idle artificially busy and for making each of the busy trunks artificially busy as soon as they become idle.

3. In a telephone system, an automatic exchange, a manual exchange, a two conductor trunk line extending from said automatic exchange to said manual exchange, a relay in said trunk line at said automatic exchange normally connected to one of the talking conductors of said trunk line, and means comprising a position busying key at the manual exchange for operating said relay over only one of said talking conductors to busy said trunk line at the automatic exchange.

4. In a telephone system, an automatic exchange, a manual exchange, a two conductor trunk line extending from said automatic exchange to said manual exchange, call register sets in said manual exchange accessible to said trunk line, a relay in said trunk line at said automatic exchange normally connected to one of the talking conductors of said trunk line, and means operated when all said register sets become busy for causing the energization of said relay over only one of said talking conductors to busy said trunk line at the automatic exchange.

5. In a telephone system, an automatic exchange, a manual exchange, a two conductor trunk line extending from said automatic

- exchange to said manual exchange, call register sets in said manual exchange accessible to said trunk line, a relay in said trunk line at said automatic exchange normally connected to one of the talking conductors of said trunk line, a switch in said manual exchange for automatically preselecting idle register sets, and means operated when said switch is hunting for an idle register set for causing the operation of said relay to busy said trunk line at the automatic exchange. 5
6. In a telephone system, an automatic exchange, a manual exchange, a two conductor trunk line extending from said automatic exchange to said manual exchange, a relay in said trunk line at said automatic exchange normally connected to one of the talking conductors of said trunk line, a fuse in the manual exchange by means of which the apparatus in the manual end of said trunk line is connected to a source of current for operating purposes, and means operative responsive to the blowing of said fuse for causing the operation of said relay over one of said conductors to busy said trunk line at the automatic exchange. 10
7. In a telephone system, an automatic exchange, a manual exchange, a two conductor trunk line extending from said automatic exchange to said manual exchange, call register sets in said manual exchange accessible to said trunk line, a relay in said trunk line at said automatic exchange normally connected to one of the talking conductors of said trunk line, a test jack in said manual exchange by means of which the trunk line and said register sets in said manual exchange are tested, and means responsive to the seizure of said trunk line in the manual exchange by way of said test jack for causing the operation of said relay over one of said conductors to busy said trunk line at the automatic exchange. 15
8. In a call indicator system, a calling line, a cord circuit accessible to said line, automatic register sets for registering called telephone numbers, a switch associated with said cord circuit, means for operating said switch to preselect an idle register set, means for extending a connection from said line to said cord circuit, a source of signalling current, and means responsive to the calling party dialling during the preselecting operation of said switch for connecting said source to said line. 20
9. In a call indicator system, a calling line, a cord circuit accessible to said line, automatic register sets for registering called telephone numbers, a switch associated with said cord circuit, means for operating said switch to preselect an idle register set, means for extending a connection from said line to said cord circuit, a source of signalling current, and means responsive to the calling party dialling for connecting said source to said line in case said switch has preselected an open trunk. 25
10. In a call indicator system, a register set comprising a plurality of register switches, a restoring magnet for each of said switches, a circuit common to all of said magnets adapted when closed for energizing said magnets, a relay included in said circuit and adapted to be energized in series with any one or all of said magnets, and contacts on said relay for rendering said set artificially busy until all said switches have been returned to normal position. 30
11. In a call indicator system, a register set comprising a plurality of register switches, a restoring magnet for each of said switches, a circuit common to all of said magnets adapted when closed for energizing said magnets, a relay included in said circuit and adapted to be energized in series with any one or all of said magnets, a holding conductor incoming to said set having a potential connected thereto when in use for rendering said set busy, a second relay in said set shunted by the potential on said holding conductor, said second relay operative when the potential is removed from the holding conductor for closing said common circuit, and contacts on said first relay for rendering said set artificially busy until all of said switches have been returned to normal position. 35
12. In a call indicator system, a manual exchange, trunk lines incoming from an automatic exchange and terminating in plug ended cord circuits in said manual exchange, means operative when a call is received for displaying the called number and for identifying the cord circuit in use, and a key common to all said cord circuits momentarily operated by the operator in case the line is busy for causing the busy signal to be continuously transmitted from said cord circuit to the calling subscriber until the calling subscriber hangs up his receiver. 40
13. In a call indicator system, a manual exchange, trunk lines incoming from an automatic exchange and terminating in plug ended cord circuits in said manual exchange, means operative when a call is received for displaying the called number and for identifying the cord circuit in use, a busy relay in each of said cord circuits adapted when energized to transmit a busy signal to the calling subscriber connected thereto, a key common to all said cord circuits momentarily operated in case the called line is busy for causing only the busy relay in said cord circuit in use to be energized, and a locking circuit for maintaining said busy relay energized until the calling subscriber hangs up. 45
14. In a telephone system, a manual exchange, an automatic exchange, a trunk line in said automatic exchange extending to and terminating in said manual exchange, call register sets comprising register switches in 50

said manual exchange, a step by step switch in the manual exchange associated with said trunk line for preselecting an idle register set, a switching relay in said trunk line at the manual exchange operated responsive to the seizure of said trunk line at said automatic exchange for seizing said preselected register set, and means in said trunk line at the manual exchange for opening the circuit of said switching relay to prevent its operation during the preselecting operation of said switch,

15. In a telephone system, a manual exchange, trunk lines terminating in cord circuits in said exchange, automatic substations having access to said trunk lines for calling subscribers in the manual exchange, a plurality of register sets for registering the telephone numbers of called manual stations, an automatic step by step switch individual to each cord circuit for connecting its associated cord circuit with an idle register set when the cord circuit is taken into use, and a differential relay in each cord circuit for controlling said switches to preselect idle register sets ahead of calls.

16. In a telephone system, a manual exchange, a trunk line terminating in a cord circuit in said exchange, automatic substations having access to said trunk line for calling subscribers in the manual exchange, a plurality of register sets for registering the telephone numbers of called manual stations, an automatic step by step switch for preselecting idle register sets ahead of calls, and a test relay in said cord circuit having a pair of contacts for controlling the operation of said preselecting switch and also controlling the operated condition of said relay when an idle register set is preselected.

17. In a call indicator system, a plurality of register sets normally accessible to calling automatic subscribers for registering the digits in a called telephone number, a reserve register set artificially made busy and normally inaccessible to calling automatic subscribers, and means operative when all said plurality of register sets are in use for automatically rendering said reserve register set accessible to calling automatic subscribers.

18. In a telephone system, a manual exchange, trunk lines terminating in cord circuits at the manual exchange, automatic substations having access to said trunk lines for calling subscribers in the manual exchange, a plurality of register sets normally accessible to calling automatic substations for registering the digits in a called telephone number, a reserve register set artificially made busy and normally inaccessible to calling automatic substations, means operated responsive to all said plurality of register sets being taken into use for rendering all of said trunk lines which are idle artificially busy and for rendering said reserve register set accessible to calling

automatic substations, and means for selecting said reserve register set in case one of said trunk lines was seized before said trunk lines were made busy.

19. In a telephone system, a manual exchange, trunk lines terminating in cord circuits at the manual exchange, automatic substations having access to said trunk lines for calling subscribers in the manual exchange, a plurality of register sets for registering the digits in a called telephone number, a reserve register set, a plurality of switches each one of which is individual to one of said cord circuits for preselecting idle register sets, said reserve set artificially made busy to said switches, means for taking into use said plurality of register sets for the purpose set forth, means operated responsive to all said plurality of register sets being taken into use for rendering all of said trunk lines which are idle artificially busy and for rendering said reserve register set idle, and means for seizing said reserve register set in case one of said trunk lines was seized during the interim in which the last idle one of said plurality of register sets was taken into use and the trunk lines were artificially made busy.

20. In a telephone system, a manual exchange, trunk lines terminating in cord circuits at the manual exchange, means whereby automatic subscribers have access to said trunk lines for calling subscribers in the manual exchange, a plurality of register sets for registering the digits in a called telephone number, a reserve register set, a plurality of switches each one of which is individual to one of said cord circuits for preselecting idle register sets, said reserve register set artificially made busy to said switches, means for taking into use said plurality of register sets for the purpose set forth, means operated responsive to all said plurality of register sets being taken into use for rendering all of said trunk lines which are idle artificially busy and for rendering said reserve register set idle, means for seizing said reserve register set in case one of said trunk lines was seized during the interim in which the last idle one of said plurality of register sets was taken into use and the trunk lines were artificially made busy, dead bank contacts in banks of said switches artificially made busy, and means operated responsive to the seizure of said reserve register set for removing the artificially busy potential from said dead bank contacts thereby establishing stopping positions for said preselecting switches.

21. In a telephone system, means for connecting a calling and a called line comprising a plug ending cord circuit, a ringing circuit including a conductor of said cord circuit, a ring-cut-off circuit including a conductor of the called line and the said conductor of said cord circuit, and means effective after the

- ring is cut off for giving the calling subscriber an audible ring-back tone over said ring-cut-off circuit.
22. In a telephone system, means for connecting a calling and a called line comprising a plug ending cord circuit, a ringing circuit including the tip conductor of said cord circuit, a ring-cut-off circuit including the tip conductor of the called line and the tip conductor of said cord circuit, and means including a third circuit for giving the calling subscriber an audible ring-back tone by induction from said third circuit into said ring-cut-off circuit.
23. In a telephone system, a plurality of lines, a plurality of trunk lines, a plug ended cord circuit adaptable for connection with said lines and trunk lines, means in said cord circuit for automatically applying a source of ringing current as soon as connection is completed with any of said lines or trunk lines, a circuit common to all of said trunk lines for disabling the automatic application of said source when said cord circuit is connected to one of said trunk lines, and means whereby said circuit also connects a ring-back tone to the cord circuit which is audible to the calling subscriber.
24. In a telephone system, a trunk line, means including a cord circuit for connecting a calling line with said trunk line, said cord circuit adapted to automatically apply a source of ringing current to said trunk line when connected thereto, and a circuit in said trunk line established responsive to the connection of said cord circuit with said trunk line for disabling the automatic application of said ringing current and for transmitting an induced ring-back tone to the calling subscriber.
25. In a call indicator system, a manual exchange, trunk lines incoming from an automatic exchange and terminating in plug ended cord circuits in the manual office, means common to said cord circuits operative when a call is received for displaying the called number and for identifying the cord circuit in use, a relay in said cord circuit adapted when energized for reversing the direction of the flow of current in said trunk line, and means in said cord circuit and under the joint control of the calling and called subscribers for energizing said relay.
26. In a telephone system, a register set accessible to a calling automatic subscriber for registering the digits in a called telephone number, said set comprising a switch for each digit, an indicating device for displaying the registered number to an operator, means for causing the complete number to be displayed when the last digit thereof is registered, a time mechanism set in motion each time a digit switch is seized, means for releasing said time mechanism to normal each time a digit switch is operated, and means controlled by said mechanism for causing all the registered digits to be displayed after a definite time interval.
27. In a call indicator system, a register set comprising a plurality of register switches, a restoring magnet for each of said switches, means common to all said switches for operating said magnets, and means controlled by said last means for making said set artificially busy until all said switches have been returned to normal position.
28. In a telephone system, a first exchange and a second exchange, trunk lines comprising only two conductors connecting said exchanges, means for seizing any one of said trunk lines, a line relay in the seized trunk line in the second exchange energized responsive to said seizure over a circuit including only one conductor of said trunk line, and means in said trunk line at both exchanges responsive to said seizure for completing a bridge circuit including the two conductors of said trunk line in series to maintain said relay energized.
29. In a telephone system, a first exchange and a second exchange, trunk lines comprising only two conductors connecting said exchanges, a third conductor for each trunk line in the first exchange, automatic switches in the first exchange, means responsive to a call by a calling subscriber for operating a plurality of said switches to seize an idle one of said trunk lines, a relay in said trunk line in the first exchange energized responsive to said seizure for connecting a busying potential to the third conductor of said seized trunk line, a circuit including only one conductor of said trunk line for maintaining said relay energized, and means controlled by the calling subscriber for closing said circuit and for only temporarily removing said busying potential from said third conductor to permit the release of the switches which were operated by the calling subscriber.
30. In a telephone system, a plurality of switches normally accessible to calling automatic subscribers for use in completing telephone connections, a reserve switch artificially made busy and normally inaccessible to calling automatic subscribers, and means operative when all said plurality of switches are in use for automatically rendering said reserve switch accessible to calling automatic subscribers.
31. In a telephone system, trunk lines, calling subscribers' lines having access to said trunk lines, a plurality of switches accessible to calling subscribers' lines for use in completing telephone connections, a reserve switch artificially made busy and normally inaccessible to calling subscribers' lines, means operative when all said plurality of switches are taken into use for rendering said trunk lines which are idle artificially busy

and for rendering said reserve switch accessible to calling subscribers' lines, and means for selecting said reserve switch in case one of said trunk lines was seized before said 5 trunk lines were made busy.

32. In a telephone system, trunk lines, calling subscribers' lines having access to said trunk lines, preselecting switches accessible to calling subscribers' lines by way of said trunk lines, a plurality of other switches accessible to said preselecting switches for use in completing telephone connections, a reserve switch artificially made busy and normally inaccessible to said preselecting switches, 10 means operated responsive to all said plurality of other switches being taken into use for rendering all said trunk lines which are idle artificially busy and for rendering said reserve switch idle, and means for seizing said 15 reserve switch in case one of said trunk lines was seized during the interim in which the last idle one of said other switches was taken 20 into use and the trunk lines were artificially made busy.

33. In a telephone system, trunk lines, calling subscribers' lines having access to said trunk lines, preselecting switches accessible to calling subscribers' lines by way of said trunk lines, a plurality of other switches accessible to said preselecting switches for use in completing telephone connections, a reserve switch artificially made busy and normally inaccessible to said preselecting switches, 25 means operated responsive to all said plurality of other switches being taken into use for rendering all said trunk lines which are idle artificially busy and for rendering said reserve switch idle, means for seizing said reserve switch in case one of said 30 trunk lines was seized during the interim in which the last idle one of said other switches was taken into use and the trunk lines were artificially made busy, dead bank contacts in the banks of said preselecting switches artificially 35 made busy, and means operated responsive to the seizure of said reserve switch for removing the artificially busy potential from said dead bank contacts thereby establishing stopping positions for said preselecting switches.

34. In a telephone system, a link circuit for extending telephone calls, an automatic step-by-step hunting switch individual to said link circuit, other switches accessible to said hunting switch, and a differential relay in said link circuit for controlling said hunting switch to preselect an idle one of said other switches ahead of calls.

35. In a telephone system, a link circuit for 50 extending telephone calls, an automatic step-by-step hunting switch individual to said link circuit, other switches accessible to said hunting switch, a relay in said link circuit, means for energizing said relay, and contacts 55 on said relay closed responsive to its energiza-

tion for causing the operation of said hunting switch and for causing a rapid deenergization of said relay when an idle one of said other switches is encountered to open said contacts to stop the hunting operation of said switch. 70

36. In a telephone system, automatic trunk selecting mechanism, trunk lines accessible thereto, each of said trunk lines being non-selectable to said switching mechanism under certain conditions, a plurality of digit 75 registers, register connecting mechanism for connecting said registers to idle ones of said trunk lines, and a relay controlled over a trunk line responsive to the connection of a register thereto for rendering the trunk line selectable to said trunk selecting mechanism. 80

37. In a telephone system, an automatic office, a manual office, a group of trunk lines extending from said automatic office to said manual office, switching mechanism in said manual office for completing to manual lines terminating therein connections extending from the automatic office to the manual office over said trunk lines, call indicating equipment including registers in said manual office for indicating to the manual operator the desired numbers, preselecting switching mechanism for effecting connection between said registers and said trunk lines, automatic switching mechanism in the automatic office 95 having access to said group of trunk lines, and means in said automatic office responsive to the connection of a register in the manual office to any one of said trunk lines for rendering the trunk line selectable to said switching mechanism in the automatic office. 100

38. In a multi-office telephone system, a trunk selecting mechanism, an inter-office trunk line accessible but non-selectable at one end to said mechanism, means for extending a 105 connection from the other end of said trunk line, and means for thereupon rendering said trunk line selectable to said trunk selecting mechanism.

39. In a multi-office telephone system, an inter-office trunk line, means at one end thereof for indicating that the trunk line is in a non-useable condition, means for linking an extension to the other end of the said trunk line, and means for thereupon removing the 110 non-useable indication from the said one end of the trunk line.

40. In a multi-office telephone system wherein inter-office trunk lines are maintained unselectable at one office when they are not connected to receiving apparatus at the other office, means effective upon the connecting of a trunk line to receiving apparatus for removing the unselectable condition. 115

41. In a telephone system wherein trunk lines are maintained artificially busy at one end when they are not connected to receiving apparatus at the other end, means responsive to the connection of a trunk line to receiving apparatus for removing the busy condition. 120

dition, and a circuit including a talking conductor of said trunk line for controlling said means.

In witness whereof, I hereunto subscribe my name this 24th day of February, A. D. 1927.

RUDOLPH FRANK STEHLIK.
